(57) CLAIM

The ornamental design for a slip-resistant floor mat, as shown and described.

DESCRIPTION

FIG. 1 is a top perspective view of the slip-resistant floor mat of the instant invention;

FIG. 2 is a top view thereof;

FIG. 3 is a bottom view thereof;

FIG. 4 is a front elevational view thereof;

FIG. 5 is a section view thereof taken along lines 5—5 of FIG. 2; and,

FIG. 6 is a reduced scale environmental view thereof illustrating the claimed design within a complete floor mat.

The parts of the Figures shown in broken lines are for illustrative purposes and form no portion of the claimed design.

1 Claim, 5 Drawing Sheets
